UNITED STATES PATENT OFFICE.

MYRON H. RICHARDSON AND ALFRED D. ANTOINE, OF CHICAGO, ILLINOIS, AS
SIGNORS TO ADVANCE MACHINE COMPANY, OF CHICAGO, ILLINOIS, A CORPORATION
OF ILLINOIS.

VENDING MACHINE.

Application filed April 19, 1926. Serial No. 102,882.

This invention relates to improvements in vending machines of the check controlled type, and one of the objects of the same is to provide an improved machine of this character for vending cards or sheets, and improved means for positively delivering the card and for insuring the delivery of only the proper or predetermined number of cards for which the machine is set. 10 A further object is to provide improved means whereby the machine may be readily adjusted to compensate varying thickness of the cards and for also varying the number of cards to be ejected upon each operation 15 of the machine.

To the attainment of these ends and the accomplishment of other new and useful objects as will appear, the invention consists in the features of novelty in substantially 20 the construction, combination and arrangement of the several parts, hereinafter more fully described and claimed and shown in the accompanying drawings illustrating this invention; and in which,

25 Figure 1 is a front elevation of a machine of this character constructed in accordance with the principles of this invention.

Figure 2 is a rear elevation, partly broken away and with parts omitted, and with the 30 rear of the casing removed.

Figure 3 is a vertical sectional view taken on line 3—3 Figure 2.

Figure 4 is a horizontal sectional view taken on line 4—4 Figure 2, and with parts 35 broken away.

Figure 5 is an irregular horizontal sectional view taken on line 5—5 Figure 2.

Figure 6 is a detailed vertical sectional view taken on line 6—6 Figure 2 on an enlarged scale.

Figure 7 is a fragmentary view of Figure 6 showing some of the parts in a different position.

Figure 8 is a detailed perspective view of 45 the card or sheet ejector or slide.

Figure 9 is an enlarged diagrammatic view illustrating the operation of the ejector upon the cards.

Figure 10 is a view in elevation of the 50 check carrier showing the means for retaining a check against delivery from a check carrier when there are no articles in the machine to be vended.

Figure 11 is a detailed sectional view showing the ends of the gage members and the adjacent portions of the partition. 55

Referring more particularly to the drawings, the numeral 10 designates generally a casing of any desired size and configuration having a slot 11 in the front thereof through which the cards or sheets are ejected, and the casing is also provided with a removable back 12 secured in position in any suitable manner.

The casing thus constructed may be of 65 any desired size and configuration, but in the present form of the invention is illustrated as being substantially rectangular in cross section, and of a capacity for holding two different and independent supplies of 70 cards.

The device is adapted to be actuated and controlled by check controlled mechanism having operating handles 13 at the front of the casing and check insertion slots 14. 75

Any suitable check controlled mechanism may be employed for the purpose but the particular mechanism especially adapted for use in connection with this machine is shown and described in Patent 1,452,721, issued 80 April 24, 1925, to Alfred D. Antoine.

The casing is provided with a horizontal partition 15 to form an upper and a lower chamber, the upper chamber being preferably divided by one or more partitions 16 85 to form two compartments or magazines 17 therein, and in which magazines the superposed cards or sheets 18 that are to be dispensed, are arranged.

The cards rest upon the horizontal partition 15 and this partition is so disposed that it will form the bottom of the slot or opening 11 through which the cards are ejected.

As the construction and operation of the 95 mechanism for vending the supplies of cards from both of the magazines is the same, the description of one will apply equally as well to them both.

Within the magazine and adjustably secured against the front wall thereof and above the partition 15, is a plate 19 held in position by means of a screw 20 passing through a suitable slot 21 in the body of the plate. Additional screws 22 also pass 105 through slots 23 in the plate.

The lateral edges 24 of the plate are deflected so as to form guides for gage members 25 that move against the respective flanges, and which gage members are preferably held in position by means of pins or projections 26 carried thereby and which project into and operate in suitable slots 27 in the plate 19.

The lower extremities of these gage members are preferably tapered or beveled as at 28, and are adapted to normally stand in close proximity to the partition 15, being yieldingly held in this position by means of a suitable elastic member 29 in the form of a spring, the body of which is coiled about an anchor member 30 carried by the plate 19. The ends of the spring 29 engage and rest upon the upper extremities of the gages 25 and tend normally to assist in moving the gage members downwardly and to hold the extremities 28 of the gage members in close proximity with the partition 15. In this position of the gage members the projections 26 will engage and rest against the bottoms of the slots 27 in the plate 19. The distance that the ends of the gages 25 are to be maintained above the partition 15 is controlled by the thickness of the card or sheet to be vended, or the number of cards which are to be projected upon a single operation of the machine.

This is accomplished by reason of the fact that the plate 19 which carries the gage members 25 may be bodily adjusted when the screws 20—22 are loosened and is held against adjustment when these screws are tightened. The gage members being free to move upwards from a fixed point prevent the machine from clogging that otherwise might be caused by a variation in the thickness or some other imperfections of the card or sheet.

Arranged behind the member 19 is a member 31 which is provided with a groove or notch 32 disposed in alignment with a slot 33 in the plate or member 19, so that by loosening the screws 20 and 22 and inserting an implement through the slot 33 and into the notch 32, the member 19 may be raised or lowered through the manipulation of the implement thus inserted and while the plate or member is held in this adjusted position by this implement, the screws 20 and 22 may be tightened.

The cards 18 are placed upon the partition 15 in rear of the gages 25, and the bottoms of the gage members being tapered, the danger of raising the gages by the insertion of an implement through the slot 11 will be prevented, especially by reason of the fact that the gages 25 are laterally spaced from each other.

The cards are ejected from the bottom of the supply by means of a slide or ejector designated generally by the reference numeral

34 which is preferably provided with laterally projecting arms 35 that move in guideways 36 beneath the partition 15.

The ejector is provided with an upwardly inclined portion 37, and a downwardly projecting portion 38, to which latter is secured an upright plate 39 having an upwardly and rearwardly extending beveled upper edge 40 which is disposed at the end of the upwardly inclined portion 37 of the ejector so as to project thereabove.

This plate 39 is adjustably secured in position preferably by means of screws 41 passing through slots 42 in the plate, so that by loosening the screws 41 the plate 39 may be adjusted with respect to the ejector 34.

As a means for thus adjusting the plate 39 there may be provided a support 43 which projects under the plate 39 and upon which the plate is adapted to rest, screws 40 being provided which pass through the plate 43 and into a portion 44 of the ejector 37.

It will therefore be manifest that by loosening the screws 41 and then adjusting the screws 40, the adjustment of the plate 39 with respect to the ejector 34 may be effected, after which the screws 41 may be tightened to hold the plate in position.

The beveled edge 40 of the plate 29 is adjusted so as to project above the inclined surface 37 for a distance substantially equal to the thickness of the card to be dispensed, or of several cards when more than one is to be delivered.

The cards 18 when superposed and when being delivered have a tendency to curl upwardly at the rear edge or end thereof and in order that the plate 39 will engage behind the edge of the lowermost card, the inclined surface 37 is provided so that the rear edge of the lowermost card will drop behind the plate 39 when the ejector 34 is moved to the limit of its backward movement, and the edge of the card will be held in a proper position to be engaged by the plate 39.

By inclining the edge 40 of the plate 39 rearwardly and upwardly all danger of the edge of the plate 39 injuring the lowermost card and thereby "clogging" the machine will be avoided. Should the cards be of slightly different thickness, the lowermost card will be engaged by the plate 39 while the edge of the next adjacent card will slide over the inclined edge 40 of the plate 39 as shown in diagram in Figure 9.

As a means for holding the cards from moving rearwardly with the ejector, projections in the form of straps or bars 45 may be provided on the back 12 of the case.

A weight 46 is provided in the magazine 17 and is concaved, the extremities of the weight engaging the extremities of the cards 18.

The weight 46 is provided with a slot or opening 47 therethrough, and the partition

15 is also provided with a slot therethrough for purposes to be set forth. The ejector 34 is provided with a slot 49 therethrough also for a purpose to be hereinafter set forth.

5 The ejector is adapted to be reciprocated by means of a rocking member 50, pivotally mounted as at 51. The member 50 preferably embodies spaced arms, the extremities 52 of which are disposed in proximity to 10 the partition 15 and each of the arms is provided with a bifurcated portion 53 opening through the upper extremities thereof, and into which bifurcations projections 54 on the ejector 34 extend, so that when the 15 member 50 is rocked a reciprocatory and sliding movement will be imparted to the ejector 34.

Thus it will be seen that when the ejector 34 is moved rearwardly the edge of the plate 20 39 will engage the lower face of the lowermost card 18, until the plate has been moved beyond the rear edge of the card. This will permit the rear edge of the lowermost card 25 to drop upon the inclined surface 37 behind the edge of the plate 39 and the inclined surface will hold the edge of the card in a position to be engaged by the plate and ejected when the ejector moves forwardly.

The card may then be removed from the 30 machine by grasping the projecting end of the card and withdrawing it through the slot 11.

As a means for preventing the operation of the machine when the magazine 17 is empty, 35 there is provided a pivotally mounted member 55 one extremity of which projects through the slot 49 in the ejector 34, and also through the slot 48 in the partition 15, into the magazine.

40 When no cards are in the magazine the member 55 will project through and beyond the partition 15 and also into the slot 47 in a manner to be later set forth.

The check controlled mechanism herein referred to embodies a check carrying disc 45 56 which is rotatable by means of the handle 13. The disc is provided with an open check seat 58 which is adapted to be inverted when the disc is rotated, so as to deliver the check 59 into the machine for connecting the handle 13 with a cam 60 for actuating the latter. The cam is adapted to engage a projection 61 carried by the member 50 to rock the latter in one direction, 55 and to engage a projection 62 also carried by the member 50, to rock the latter in the opposite direction, and thereby impart a swinging movement to the member 50 which will cause the reciprocation of the ejector 60 34.

A member 63 is pivotally mounted at one end as at 64, and is provided with a finger or projection 65 that is adapted to extend through a suitable opening so as to be projected to a position adjacent the path of

movement of the check 59 in the check seat 58, when the disc 56 is rotated to a position to deliver the check from the seat.

When the finger 65 is in the position shown in Figures 5 and 9 the check will be 70 held against delivery from its seat and will be returned to the operator.

When the finger 65 is withdrawn, the check 59 will be delivered from its seat on to a support 66, and when the check carrier 75 56 then returns, it will force the check 59 between the support 66 and the arm 67 to render the cam 60 active for rocking the member 50.

The specific construction of the check controlled mechanism, however, forms no part of the present invention.

The finger 65 of the member 63 is controlled in its operation by the articles in the magazine which rest upon and depress 85 the member 55, the operation being as follows:

A rock shaft 68 (see Figure 5) preferably in the form of a rod or wire is journaled in a suitable bearing 69. One end of the shaft is deflected so as to extend over a projection 71 on the member 55 (see also Figure 3). The other portion of the member 68 depends as at 72, and projects into an opening 73 in the member 63, a spring 74 95 being provided which tends normally to move the finger 65 into a position to engage and hold a check 59 in its seat. This spring 70 also tends normally to raise the extremity of the member 55 so that it will 100 project through the opening 49 in the ejector 34 through the opening 48 in the partition 15 and beyond the partition, so that when a supply of cards 18 is placed in the magazine the cards will engage and depress the end 105 of the member 55 and rock the member about its pivot and against the stress of the spring 74 to withdraw the finger 55, so that the check 59 will be delivered from its seat in the check carrier 50 when the latter is 110 rotated to invert the seat.

Thus it will be seen that as long as any cards are in the magazine, the weight thereof together with the weight 46, will hold the finger 65 retracted.

When the magazine is empty, the spring 74 will project the finger 65 and the extremity of the member 55 will rise to permit such operation of the member 63.

The opening 47 in the weight 46 is provided so as not to interfere with this operation of the member 55 when all of the cards have been dispensed from the magazine.

It will therefore be manifest that with a machine of this character the cards will be 125 ejected successively by the reciprocation of the ejector after the insertion of the proper check.

When cards are in the magazine the mechanism will operate to deliver one card upon 130

each operation of the ejector, but when the magazine is empty of cards, the finger 65 will hold the check 59 against delivery into the machine from the check seat and the check will be returned to the operator.

The partition 15 may be provided with ribs or projections 15^a disposed directly beneath the gages 25 so that in the event the cards or sheets have a tendency to curl up along their side edges, the edges will have positive supporting surfaces beneath the gages.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. In a vending machine, a magazine for articles to be vended, said machine having a delivery opening, a plurality of loosely mounted members spaced from each other in directions lengthwise of and projecting across said opening and freely and separately movable transversely thereof, a support for the said members, means for adjusting the support, and means for ejecting an article through the said delivery opening and beneath the said members.
2. In a vending machine, a magazine for articles to be vended, said machine having a delivery opening, a plurality of loosely mounted members spaced from each other in directions lengthwise of and projecting across said opening and freely and separately movable transversely thereof, a support for the members, means for adjusting the support, and means for ejecting an article through the said delivery opening and beneath the said members, the lower extremities of the said members being tapered.
3. In a vending machine, a magazine for articles to be vended, said machine having a delivery opening, a plurality of loosely mounted spring controlled members co-operating with said delivery opening and operating transversely thereof, said members being adapted for movement separately with respect to each other, means for simultaneously and bodily adjusting said members to vary the size of the said delivery opening, and means for ejecting the articles through said opening and beneath the said members.

4. In a vending machine, a magazine for articles to be vended, said machine having a delivery opening, a gage member, a support for the gage member, said gage member being mounted upon the support for bodily movement therewith and for free movement with respect thereto, and means for adjusting the said support for bodily moving the gage member, the said means embodying a

shoulder adjacent one face and separate from the support, there being an opening in the support adjacent said shoulder and into which opening an implement may be inserted from the other side of the support to simultaneously engage the said shoulder and the wall of said opening whereby the support will be adjusted by a movement of the implement while in engagement with the shoulder of said wall.

5. In a vending machine, a magazine for articles to be vended, said machine having a delivery opening, a plate like support, a gage member mounted upon the support for movement therewith and freely with respect thereto, and a shoulder separate from and adjacent one face of the support, there being an opening in the said plate in alignment with said opening whereby when an implement is inserted into said opening from the other side of the support to engage the shoulder and then rotated, the said plate and gage member will be adjusted.

6. In a vending machine, a magazine for articles to be vended, said machine having a delivery opening, a plate like support, a gage member mounted upon the support for movement therewith and freely with respect thereto, a shoulder separate from and adjacent one face of the support, there being an opening in the said plate in alignment with said opening whereby when an implement is inserted into said opening from the other side of the support, to engage the said shoulder and then rotated, the said plate and gage member will be adjusted, means tending normally to move the said gage member in one direction with respect to said support and for yieldingly maintaining the gage member projected across said delivery opening, and means for ejecting an article through the delivery opening and beneath said gage member.

7. In a vending machine, a magazine for a superposed supply of cards to be vended, said machine having a delivery opening, a slide for successively ejecting the cards from the bottom of the supply, means for reciprocating the slide, the rear portion of the slide inclining upwardly and backwardly, and an upright plate like member adjustably secured to the slide at the end of said upwardly inclined portion of the slide to project thereabove.

8. In a vending machine, a magazine for a superposed supply of cards to be vended, said machine having a delivery opening, a slide for successively ejecting the cards from the bottom of the supply, means for reciprocating the slide, the rear portion of the slide inclining upwardly and backwardly, and an upright plate like member adjustably secured to the slide at the end of said upwardly inclined portion of the slide to project thereabove the upper edge of the

said plate above the surface of said inclined portion being beveled upwardly and rearwardly. 60

9. In a vending machine, a magazine for a superposed supply of cards to be vended, said machine having a delivery opening, a slide for successively ejecting the cards from the bottom of the supply, means for reciprocating the slide, the rear portion of the 10 slide inclining upwardly and backwardly, an upright plate like member adjustably secured to the slide at the end of said upwardly inclined portion of the slide to project thereabove, and means controlled by the 15 cards in the magazine for controlling the reciprocation of the said slide. 65

10. In a vending machine, a magazine for a superposed supply of cards to be vended, said machine having a delivery opening, a slide for successively ejecting the cards from the bottom of the supply, means for reciprocating the slide, the rear portion of the slide inclining upwardly and backwardly, an upright plate like member adjustably secured to the slide at the end of the 20 said upwardly inclined portion of the slide to project thereabove, and means for adjusting the said plate with respect to the 25 said slide. 70

11. In a vending machine, a magazine for a superposed supply of cards to be vended, said machine having a delivery opening, a slide for successively ejecting the cards from the bottom of the supply, means for reciprocating the slide, the rear portion of the slide inclining upwardly and backwardly, an upright plate like member secured to the slide at the end of the said upwardly inclined portion of the slide to project thereabove, and a weight in the magazine resting upon the cards, the said weight being concaved in a direction that the extremities of the weight will engage and rest against the extremities of the cards. 75

12. In a vending machine, a magazine for articles to be vended, said machine having a delivery opening, a support for the articles adjacent the opening, a plurality of gage members independent of each other and 40 projecting across said opening and freely movable transversely thereof, projections extending above the surface of the support and directly beneath the ends of the respective gages, and means for ejecting the 45 articles through said opening. 80

13. In a vending machine, a magazine for a superposed supply of cards to be vended, said machine having a delivery opening, a slide for successively ejecting the 50 cards from the bottom of the supply, means for operating the slide, a formation on the slide to engage behind the rear edge of the card, and a weight in the magazine resting upon the cards, the edges of said weight projecting beyond the remaining portion of the lower face of the weight whereby the weight will be supported by its extremities by the extremities of the cards. 85

14. In a vending machine, a magazine for the articles to be vended, said machine having a delivery opening, a plurality of members separate and spaced from each other in directions lengthwise of said opening and projecting across said opening, said members being loosely mounted and freely and separately movable transversely of the opening, and means for ejecting the articles through said opening and beneath the said members. 90

15. In a vending machine, a magazine for the articles to be vended, said magazine having a delivery opening, a loosely mounted and freely movable member projecting across said opening, a slide for successively ejecting the articles from the bottom of the supply and beneath said member, means for reciprocating the slide, means controlled by the supply of articles in the magazine for controlling the reciprocation of the slide, the last recited 95 means embodying a pivotally mounted member, and means tending normally to project the end of the last recited member into the magazine to be engaged and depressed by the articles in the magazine. 95

16. In a vending machine, a magazine for the articles to be vended, said magazine having a delivery opening, a loosely mounted and freely movable member projecting across said opening, a slide for successively ejecting the articles from the bottom of the supply and beneath said member, means for reciprocating the slide, means controlled by the supply of articles in the magazine for controlling the reciprocation of the slide, the last recited means embodying a pivotally mounted member, said slide having an elongated opening therethrough, and means tending normally to project the end of the last said member into the magazine and through said elongated opening to be engaged and depressed by the articles in the magazine. 100

In testimony whereof we have signed our names to this specification, on this 12th day of April, A. D. 1926. 105
